UNITED STATES PATENT OFFICE.

RUDOLF BREBACH, OF LEIPZIG-REUDNITZ, GERMANY.

AUTOMATIC ELECTRICAL CUT-OUT DEVICE.

No. 852,766.

Specification of Letters Patent.

Patented May 7, 1907.

Application filed July 21, 1904. Serial No. 217,582.

To all whom it may concern:

Be it known that I, RUDOLF BREBACH, a subject of the King of Saxony, and residing at No. 10 Kohlgartenstrasse, in the city of Leipzig-Reudnitz, in the Kingdom of Saxony, German Empire, have invented a certain new and Improved Automatic Electrical Cut-Out Device, of which the following is a specification.

10 This invention relates to an automatic electrical cut-out device, and my improvements in the same relate to certain combinations and arrangements of parts as are fully described hereinafter.

15 My invention is shown in plan, in dia-grammatical representation, in the accom-panying drawing.

In this figure, A is the base-plate of a junction - box which has binding - posts or 20 screws for feed- or other wires. The box contains a plate upon which are mounted means for automatically interrupting and re-establishing the circuit.

25 5 and 6 are the before-mentioned binding- posts. They are connected with the line-wires, by which the current is conducted to, and away from, the cut-out device. The electromotor or other electrical apparatus intended to co-operate with the cut-out device 30 is connected with this latter by wires, that enter the device through a central aperture of said base-plate A. One of these wires is connected by means of a third binding-post 4, with the bobbin s of a horse-shoe shaped electromagnet t, the armature of which is formed by a one-armed lever a connected at its fulcrum with the other end of said bobbin. The other of the said wires is connected with the binding-post 6, and thus with one of the 35 line-wires. The other line-wire is connected by the binding post 5, with a double armed lever e connected with the armature a by a rod z. The neighboring free ends of the armature a and a lever e have contact pieces c c

normally pressed against each other by a 45 spring r acting in the proper sense upon the other end of said lever. The contact pieces c c form the connection between the binding-post 5 on one side, and, through the mediation of the bobbin s and the motor etc., the 50 binding-post 6 on the other side. Therefore, the current passes through the motor etc. so long as the pieces c c are in contact with each other. The electromagnet t is, of course, constantly excited, but as long as the 55 strength of the current does not surpass a certain limit, the spring r is stronger than the electromagnet. Otherwise, however, the armature a is attracted by the electro- magnet and the lever e is moved by means of 60 the rod z, so that the contact-pieces c c are quickly separated from one another and the current is thus broken.

Having now described my invention what I desire to secure by a patent of the United 65 States is:

In an electric cut-out device, the combina- tion with an electromagnet, an armature forming a one-armed lever, a connecting- wire between the fulcrum of said armature 70 and the coil of said electromagnet, a double- armed lever located about parallelly to said first lever, opposite to the electromagnet, contact-pieces attached one to the free end of the first lever and the other to the free end of 75 the neighboring arm of the other lever, a connecting-link between the other arm of the latter and the said first lever, and a connect- ing-wire secured to the fulcrum of the said double-armed lever, for the purpose as de- 80 scribed.

In testimony, that I claim the foregoing as my invention, I have signed my name in presence of two subscribing witnesses.

RUDOLF BREBACH.
